UNITED STATES PATENT OFFICE

WILLIAM E. PRICE, OF WHITE PLAINS, NEW YORK

LANTERN

Application filed September 19, 1924. Serial No. 738,645.

This invention relates to lanterns and to mounting means therefor. More particularly, the invention is directed to lanterns for stage, display and window lighting.

5 One object of the invention is to provide a series of lanterns and mounting therefor that may be grouped in a unit and used in co-operation with an independent reflector to make available lighting effects of a wide 10 range of quality and character.

A further object of the invention is to provide a light unit of the character described including a reflector and lanterns mounted in operative relation thereto so as to provide 15 stage foot lights, and having means for lowering the lanterns below the stage so as to provide a novel and practical construction of disappearing foot lights.

Another object is to provide a lighting 20 unit constructed of few and simple parts which are relatively inexpensive to manufacture and which form a highly efficient and desirable device for the purposes described.

Other objects of this invention will in part 25 be obvious and in part hereinafter pointed out.

Certain features herein shown and described, are shown, described and claimed in my co-pending application Serial No. 738,644 30 filed in the United States Patent Office on the 19th day of September, 1924, and accordingly not claimed herein.

With the above exception the invention accordingly consists in the features of construction, combinations of elements and arrangement of parts which will be exemplified in the construction hereinafter described and of which the scope of application will be indicated in the following claims.

40 In the accompanying drawing, in which is shown one of the various possible illustrative embodiments of this invention,

Fig. 1 is a view in side elevation, partly in section, of a lighting unit embodying the invention shown in use for lighting a required area and space, as for example as foot-lights for a stage;

Fig. 2 is a view in front elevation showing 50 a group of lanterns and a portion of a mount-

ing therefor, forming the lighting unit shown in Fig. 4;

Fig. 3 is a mid-sectional view of one of said lanterns; and

Fig. 4 is a perspective view of the lantern 55 with a screen in the casing-opening replacing the door.

Referring in detail to the drawing 10 denotes a lantern pivotally mounted on a U-shaped frame 11 which is adjustably and removably secured to the lantern casing 12 by means of clamping wing screws 13. The individual frames 11 are adapted each to be firmly secured either rigidly or swivelly to a channel supporting frame 14 to form a 60 lighting unit, as, for example, like that illustrated in Fig. 2. The channel frame 14 is provided with spaced brackets 19 fastened thereto by screws 20, as shown in Figs. 1 and 2, said brackets 19 being adapted to receive 70 therethrough a shaft 21. The latter is secured to said brackets 19 by any suitable means, such as screws 22, threading into the brackets to engage said shaft 21. The channel frame 14, with the lanterns 10 thus 75 assembled, is pivotally supported for swinging on any suitable mounting. In the form shown in Fig. 2, the shaft 21 is journaled in a U-shaped frame 15 from which depends a vertical rod 16, slidable in a tubular stand 80 chion 17 having the usual adjusting screw 18.

Each lantern 10 comprises a casing 12 having a front opening normally closed by a removable door 23 that is held in place by a pair of resilient, flat, clamping straps 24 85 each of which is fastened at one end thereof to a side of the casing 12 adjacent its pivotal mounting as shown in Fig. 1. The door 23 is provided with an inturned rim-flange 23^a for seating the door in said opening and carries a lens 25 properly aligned with a bulb 26 mounted in the casing 12. The lens 25 may be secured by a spring ring 27 and retaining screw 28. Casing 12 is preferably 90 cast in a single piece having a portion 12^a of curved cross-section, properly shaped and positioned so that the inner surface 12^b thereof is adapted to serve as an efficient reflector. In order to provide a simple and inexpensive 95 construction, casing 12 may be preferably 100

formed of metal, as, for example, aluminum, or the like, so that the portion 12^a may provide a reflecting surface by simply polishing the metal.

5 Casing 12 and door 23, with the exception of lens 25 completely enclose the light, the interior surface thereof (exclusive of surface 12^b) is preferably coated with a dull black pigment to eliminate reflections from the walls of the casing interfering with those from the reflecting surface 12^b.

10 A socket 29 in which the bulb 26 is secured, may be slidably mounted lengthwise of the bottom of casing 12 for adjustment with respect to lens 25 or reflecting surface 12^b. Suitable means extending through the casing may be provided for adjusting and maintaining the bulb in desired adjusted position, as, for instance, (see Fig. 3), by a stud 30 on 15 which a wing nut 31 is mounted to control the frictional engagement of a flat spring 32 against casing 12.

15 From the above description and the drawing, it is plain that each lantern 10 may be easily adjusted to swing in vertical planes in its frame 11, while the entire unit may be swung with respect to frame 15. When the said unit is used for foot-lights in stage lighting as shown in Fig. 1, it may be positioned in 20 front of a stage 33 preferably in a depressed trough 34, but may be placed on the level with the stage if desired. A reflector 35 is provided to reflect the light from the lanterns 10 on to the stage. Said reflector 35 may be shaped to produce the desired distribution of light on stage 33 in the manner well known. When the unit is in the position shown in the full lines in Fig. 1, the stage 33 receives direct lighting from lanterns 10, either concentrated 25 as spot lights through lenses 25 in doors 23, or flood lighting when doors 23 are removed.

30 Various color screens may also be put in front of the opening in the casing 12 and held by straps 24 in place of the door 23, to produce different desired lighting effects. (See Fig. 4.)

35 By swinging the lanterns 10 to the position shown in dotted lines in Fig. 1, indirect lighting from reflector 35 is provided which may be of spot light or flood light character, depending on whether or not the doors 23 are used, or may be of various colors, as explained above.

40 The enclosed form of lighting by lanterns 10 as provided for by the invention is highly desirable for the purposes described, as "glare" may be eliminated and the kind and quality of light obtained where it is needed.

45 In arranging the lighting system in units, a combination of direct and indirect lighting may be provided for.

50 The intensity of lighting may be varied by the use of dimmers in the well known manner.

55 It will thus be seen that there is provided a device in which the several objects of this

invention are achieved and which is well adapted to meet the conditions of practical use.

60 As various possible embodiments might be made of the above invention, and as various changes might be made in the embodiment above set forth, it is to be understood that all matter herein set forth or shown in the accompanying drawings is to be interpreted as illustrative and not in a limiting sense.

65 Having thus described my invention, I claim as new and desire to secure by Letters Patent: —

70 1. In combination, a stage and a foot lighting system therefor, said system comprising a trough depressed below the level of said stage, a fixed reflector forming a side-wall of said trough, and a lighting unit supported in said trough comprising a light source and reflector pivotally mounted to provide direct and indirect lighting effects for said stage from various positions thereof in said trough.

75 2. In combination with a fixed reflector, a lighting unit associated therewith, said unit comprising a plurality of lighting elements mounted for individual pivotal movement about an axis thru said elements and means for pivotally moving said elements simultaneously as a unit about an axis parallel to and spaced from said first mentioned axis.

80 3. In combination, a stage and a foot lighting system therefor comprising a trough depressed below the level of said stage, a fixed reflector forming a side wall of said trough, a lighting unit within said trough, said unit comprising a plurality of enclosed lanterns mounted for individual pivotal movement, and means for pivotally moving said lanterns simultaneously as a unit to provide direct and indirect lighting effects for said stage.

85 In testimony whereof I affix my signature.

WILLIAM E. PRICE.
